UNITED STATES PATENT OFFICE.

CHARLES DOERING, JR., AND HENRY H. DOERING, OF CHICAGO, ILLINOIS.

LIQUID COOLING AND DISPENSING APPARATUS.

1,366,667.

Specification of Letters Patent. Patented May 2, 1918.

Application filed February 7, 1916. Serial No. 76,632.

To all whom it may concern:

Be it known that we, CHARLES DOERING, Jr., and HENRY H. DOERING, citizens of the United States, residing at Chicago, in the county of Cook and State of Illinois, have invented certain new and useful Improvements in Liquid Cooling and Dispensing Apparatus, of which the following is a description, reference being had to the accompanying drawings, which form a part of our specification.

Our invention relates to an apparatus more especially adapted for cooling drinking water or beverages and dispensing the same in predetermined quantities; the particular type of apparatus disclosed being intended to receive its supply of liquid from a visible original container or bottle; the invention contemplating a valveless construction or faucet whereby the liquid may be withdrawn in predetermined quantities; the flow of liquid from the original container or bottle being automatically regulated or controlled by the liquid-supply in the apparatus proper, as will be hereinafter set forth.

The invention also contemplates coin-operated mechanism whereby the liquid-dispensing means is controlled; said mechanism being adapted in its initial movement to issue or feed out a sanitary or paper cup; the initial or "feeding" movement of said mechanism being automatic through the insertion of a proper coin; while the further or second movement of said mechanism operates the liquid-dispensing mechanism; a complete operation of the mechanism resulting in a sanitary or paper cup being issued to the user and a predetermined quantity of liquid or beverage being dispensed.

The above enumerated objects of the invention, as well as the advantages inherent in the invention, will be more fully understood from the following detailed description of the drawings wherein:

Figure 1 is a vertical sectional view of the liquid cooling and dispensing portion of our apparatus, with the coin-operated mechanism and cup-container, as well as the original liquid-container being shown in full lines.

Fig. 2 is a perspective view of the liquid-receiving reservoir or container which is adapted to be mounted in the cooling chamber of the apparatus.

Fig. 3 is a plan view of the apparatus

shown in Fig. 1 with the top or cover of the cooling chamber removed.

Fig. 4 is a partial elevation and vertical sectional view of a modified form of our improved apparatus.

Fig. 5 is a vertical sectional view of a modified form of our invention, wherein the coin-operated mechanism and cup-issuing member are dispensed with.

Fig. 6 is a detail view, partially in section, of the liquid-dispensing or valveless faucet member disclosed in Figs. 4 and 5.

Fig. 7 is a sectional view of said member taken on the line 7—7 of Fig. 6, looking in the direction of the arrows.

Fig. 8 illustrates the coin-operated and cup-dispensing means in elevation with the outer shell or casing and a portion of the top or cover of the cooling chamber of the apparatus shown in section.

Fig. 9 is a similar view, illustrating the mechanism released through the action of an inserted coin; the cup-issuing mechanism being shown as partially operated; while its extreme outward or operated position is shown in dotted lines.

Fig. 10 is a vertical sectional view taken on the line 10—10 of Fig. 8, looking in the direction of the arrows.

Fig. 11 is a vertical sectional view taken on the offset line 11—11 of Fig. 10, looking in the direction of the arrows.

Fig. 12 is a top plan view of the coin-operated mechanism shown in Figs. 8 to 11, inclusive, with the outer cover or casing for said mechanism removed.

Fig. 13 is a detail view in perspective, of the cup-issuing element or manipulating lever.

Fig. 14 is a detail plan view of a portion of the outer cover or casing of the coin-operated and cup-issuing mechanism, with portions broken away to more clearly illustrate the coin-slot controlling mechanism.

Fig. 15 is a perspective view of a suitable type of sanitary or paper cup which may be used with our improved apparatus.

Fig. 16 is a perspective view of the coin-receiving receptacle.

In the exemplification of our invention, as disclosed in the first three figures of the drawings, the apparatus comprises the main body or tank 20, preferably made cylindrical in shape and of suitable material, such as sheet metal; the tank being divided into separate compartments arranged one above

the other; the upper compartment being provided with an insulating wall 21 so as to provide a suitable cooling chamber 22 adapted to be packed with ice; while the lower compartment 23 is adapted to provide a suitable storage chamber for an original container or bottle 24, as well as a drip and cup-receiving vessel 25.

In order to permit proper access to the storage chamber 23, the lower wall of the body or tank-portion 20 is provided with a door 26, shown in full lines in Fig. 4 and in section in Fig. 1; the door being preferably slidably mounted so as to slide along the inner side of the chamber. The door is held in proper sliding position by means of the rails 27 and 28 mounted along the top and bottom of the chamber, see Fig. 1.

The cooling chamber 22 is provided with suitable means for draining the chamber, as, for example, the drip-pipe 29 arranged in the bottom of the upper or cooling chamber 22 and at a point immediately above the drip-vessel 25; the drip-pipe 29 being preferably in the nature of a spigot, as shown, so that passage of air into the cooling chamber will ordinarily be prevented.

The cooling chamber 22 is provided with a liquid-receiving member or vessel 30, preferably made of vitreous ware, and given any desired shape or configuration, which will permit it to be inserted into the cooling chamber and at the same time provide sufficient ice-receiving space, as disclosed in Fig. 3. We prefer to form the water-receiving vessel or member 30 with the two compartments or portions 31 and 32, see Fig. 3, having communication with each other at the lower end thereof, to wit, beneath the intermediate or separating wall 33, see Fig. 1. The portion 32 is adapted to extend somewhat beyond the upper portion of the vessel 30 so as to permit it to pass through a suitable opening in the top member or cover 34 of the apparatus; the extended neck of the portion 32 being preferably provided with a flared orifice to receive the neck of the inverted original container or bottle 24, as shown in Fig. 1. We prefer to provide the flared orifice of the portion 32 with a resilient or rubber ring 35 to provide a proper cushion for the container or bottle 24, and at the same time provide a substantially airtight connection.

The portion 31, of the liquid-receiving receptacle 30, is provided with the forwardly presented outlet portion 36, preferably formed integral with the upper portion thereof. The portion 36 is provided with a discharge spout 37 which is preferably detachably secured in the opening 38 in the lower part of the extension 36, see Figs. 1 and 2. The portion 31, within the extension 36, is provided with an opening 39, see Fig. 2; and the walls on both sides of the opening 39 are

provided with the lugs 40. The lugs 40 are notched to provide a suitable bearing for the trunnions 41 formed integral with, or otherwise secured to, the spout 42 of the dipper or cup-member 43, thereby holding the member 43 in place and free to oscillate in the lugs or brackets 40; the cup or dip-member 43 being located within the portion 31 of the receptacle 30, while its spout 42 extends through opening 39 and into extension 36, as shown in Fig. 1.

The spout 42 is shown provided with the upwardly presented extension or lug 44 which is provided with the elongated slot 45, adapted to receive a pin 46 on the lower end of an arm 47 of the coin-controlled mechanism. The cup or dipper-member 43 has the upwardly presented wall 48 at the forward portion thereof in order to prevent the liquid from spilling out over the top of the member when it is tilted into the emptying or discharging position shown in full lines in Fig. 1; the dripping or intake-position of the member 43 being shown in dotted lines in said figure.

As the bottle or container 24 is provided with an extension or tube 49 which extends into a plane slightly beneath the horizontal plane occupied by the bottom wall 50 of the extension or portion 36, it is evident that the liquid in the receptacle 30 will form a seal for the bottle or container 24 as soon as the liquid in the receptacle rises to a height where the orifice of the extension or tube 49 will be covered or immersed and thereby prevent air from entering the container or bottle 24.

The top member or cover 34 of the cooling chamber is provided with a cup-holder and vending device inclosed by the inner casing 51. The casing 51 is preferably of the rectangular construction shown, and is provided with a partial bottom 52, see Fig. 11, terminating at the forward end of the receptacle in the narrow flanges 53, 53 arranged along the side walls of the receptacle, as shown in Fig. 10. The partial bottom 52 and the side flanges 53 provide support for the superimposed sanitary paper cups 54, shown in section in Figs. 10 and 11, and in full lines in Fig. 15. The paper cups, however, need not necessarily be of the particular construction or type illustrated, but of any suitable construction that will permit them to be collapsed and closely packed in the receptacle 51. The paper cups illustrated in the drawings are in the nature of an open-ended envelop, with the short wall presented downwardly and the open end toward the rear of the casing, as shown in Fig. 11.

The front wall of the receptacle 51 is provided with a transversely disposed opening or slot 55 for the passage of the plunger 56 which is adapted to slide between the side flanges 53, as shown in Fig. 10. The

plunger 56 is preferably of the construction more clearly illustrated in Fig. 13, being provided at its forward end with the cut-out or open portion 57, in order to permit the operator to properly grasp the released or issued cup after the plunger has been withdrawn or moved outwardly from the receptacle; and for that reason the forward end of the slide-member or plunger 56 is preferably bent downwardly out of the way of the cup. The downwardly presented portion is provided with a suitable handle or grasp 58. The slide member or plunger 56 is provided with a cup-engaging portion or element 59, shown in the nature of thin sheet metal, with the rearward end of the sheet 59 being provided with upturned edges 60, preferably formed in the angular manner shown in Fig. 13 so as to correspond with the short wall or open end of the cup 54 with which it engages, as shown in Fig. 11. The cup-engaging portion or element 59 is merely secured at its forward end to the plunger or slide 56, so that the member 59 may ride or extend over the partial bottom 62, as shown in Fig. 11, and thus be in constant contact with the collapsed cups as shown.

In order to maintain the superimposed cups 54 in proper frictional engagement with the plunger 56 and its cup-engaging portion 59, a suitable weight member 61 is provided; although any other suitable means may be employed.

The elongated slot 55, in the front wall of the casing 51, is made slightly larger, vertically, than the thickness of the plunger or slide 56, so as to permit a single cup 54 to pass through the slot when the plunger or slide is forced outwardly into the position shown in Fig. 9.

The body-portion of the slide 56 is provided with a downwardly extending lug 62, see Fig. 11, provided with a vertically disposed slot which receives a pin 63 mounted at the upper end of an oscillating arm 47, which latter is pivoted at the point 64 in the bottom of the casing. The bottom of the casing 51 is left open, and the insulated top or cover 34 of the liquid-containing cooling chamber is provided with an elongated slot 65 for the passage of the arm 47, as shown in Figs. 10 and 11. The pin 46, at the lower end of the arm 47, as previously described, extends into the slot 45 formed in the upwardly presented extension 44 on the spout 12 of the cup or dipper-member 43. It is evident from the construction just described that when plunger or slide 56 is moved outwardly, as shown in Fig. 9, the upper portion of arm 47 will be drawn toward the front of the casing 51, causing the lower portion of arm 47 to swing to the right in Figs. 1 and 11. This will force the cup or dipper-member 43 downwardly into the po-

sition shown in dotted lines in Fig. 1, namely into dipping position. Upon returning plunger or slide 56 to the normal position shown in Fig. 11, arm 47 will be caused to oscillate in a direction opposite to that just described, thereby causing pin 46 to slide upward in the slot 45 of projection 44, as shown in Fig. 1, which will induce the cup 43 to be oscillated on its trunnions 41 and brought upward into the emptying or discharging position indicated in full lines in Fig. 1. This position of the cup 43 permits the liquid to flow out of cup or dipper-member 43 into the discharge portion or extension 36 of vessel 30, and by means of spout 37 to the exterior of the apparatus.

As is evident from the description just given of the operation of the cup-holding and coin-operated mechanism, the initial or outward movement of plunger 56 will cause a cup to be fed from the casing 51, while the second or return movement of plunger 56, to normal position, will cause the liquid to be dispensed to the operator in a predetermined quantity.

In order that the plunger 56 may automatically be forced outward upon its release through the insertion of a proper coin, we provide suitable spring mechanism as, for example, the spring 66, one end whereof 95 engages rearward of the depending lug 67 formed on the under side of plunger 56, see Figs. 10 and 11, while the main portion of the spring is shown wound about a spool 68, and has its opposite ends held by the 100 side wall of the casing 51 and by the spool-holding standard 69, as shown at 69^a in Figs. 10 and 11.

The plunger or slide 56 is also shown provided with a depending bracket or lug 70 105 provided with a vertically disposed slot, see Fig. 11, which receives the bent end of an arm 71 which engages with the shaft of an ordinary counter or register 72, adapted to register the number of operations of the 110 slide or plunger 56, and therefore the number of coins that should be found in the apparatus. As the register or counter is of a well-known type, a detailed description thereof need not be entered into. The register or counter is suitably mounted in the lower part of the shell or casing 51, as shown in Fig. 11, with its view or sight opening presented forwardly through a suitable sight opening or slot formed in the 120 front wall of the casing.

One side wall of the casing 51 is provided with suitable coin-controlled mechanism, comprising a pair of levers 73 and 74 pivotally mounted at the points 75 and 125 76, respectively. The upper ends of the levers 73 and 74 are provided with heads 77 and 78, respectively, and these heads are provided with correlated slots 79 of different sizes; the registering or correlated slots of 130

- each head 77 and 78 being of a size slightly smaller than the diameter of the coin the composite slot is adapted to receive when the heads are in normal or the close position 5 shown in Fig. 8, so that when a proper coin is inserted and pressed sufficiently downward, as shown in Fig. 9 at A, the heads of the levers 73 and 74 will be forced apart and oscillated on their respective pivotal 10 points 75 and 76. Lever 73 is held and returned to its normal position by means of a suitable spring 80; while lever 74 is held and returned to its normal position by means of the spring 81.
- 15 Lever 73 is shown provided with a socket 82 adapted to receive the lower end of lever 74 when the levers have been oscillated into the separated position by means of a coin, as shown in Fig. 9; the lower end of lever 20 74 normally being adapted to engage with lever 73, as shown in Fig. 8, and thereby assist in maintaining the lower part of lever 73 in locking engagement with a rack 83 which is secured to the slide or plunger 56; 25 the rack 83 being secured to slide or plunger 56 by means of the bracket 84 shown in Fig. 10. The rack 83 therefore overlaps the lower edge of the short side wall of casing 51, as shown in Figs. 8, 9 and 10.
- 30 The rack 83 is provided with an upwardly presented arm 85, the upper end whereof has a shield or member 86 which is adapted to pass across the tops of the heads 77 and 78 of the levers 73 and 74, respectively, as indicated in Fig. 9. The shield or member 86 will not only force the coin or token downward sufficiently so as to cause it to become disengaged with the heads 77 and 78 and dropped into the coin-receptacle 87 located 35 beneath the short side wall of the casing 51, but also prevent any possibility of the coin being withdrawn after the levers have been sufficiently separated and the slide or plunger forced out.
- 40 45 The lower end of lever 73 is preferably shouldered so as to engage with the teeth of the rack 83. In order to prevent the too far movement of the lower end of the lever, we provide the stop 88. In the normal position of the mechanism, the lower end of lever 50 73 will be in engagement with the first tooth of the rack 83, as shown in dotted lines in Fig. 8, while complete operation of slide or plunger 56 will bring the rear end of rack 55 83 into engagement with the lower end of lever 73. The rack is provided with a number of notches or teeth with which the lever 73 will form locking engagement during its partial return to normal position.
- 60 65 By reason of this construction, it is impossible for the operator to so manipulate the slide or plunger 56, that the insertion of a single coin would enable him to secure more than one cup and dispense or obtain more than one drink. With the rack 83 pro-
- vided with a number of teeth or notches as shown, it is evident that a partial return of the slide or plunger 56, to normal position, will result in the rack, and therefore also slide or plunger 56, becoming locked 70 against a reverse or outward movement.
- The notch or socket 82, formed in lever 73, permits the proper oscillation of lever 74, namely out of locking engagement with lever 73, when a proper coin has been inserted.
- In order to prevent spring 81 from drawing the lower end of lever 74 beyond its locking contact with lever 73, we provide a stop 89; and the too far separation of the 80 heads 77 and 78 of the levers, by the insertion of a slug or token of improper diameter, is prevented by the stop or lug 90 with which the head 78 contacts, while the front wall of the casing would prevent the head 77 from being forced beyond proper position.
- Casing 51 and the mechanism mounted thereon, as well as the coin-receiving receptacle 87, are all incased by an outer covering or casing 91 which is adapted to be slid over the top of casing 51 and the mechanism secured thereto. The casing 91 is locked in place by means of a suitable lock, indicated at 92 in Fig. 11; casing 51 being permanently secured to the top or cover 34 of the 95 main portion of the apparatus.
- The top or cover 34 is preferably hinged at one side to the main body or tank of the apparatus, while the other side may be provided with a suitable lock so that access to 100 the interior of the water-receiving cooling chamber cannot be had by unauthorized individuals.
- The top of the outer shell or casing 91 is provided with a suitable coin-receiving opening 93, see Fig. 14, which registers with a similar opening 94 arranged in the top of casing 51; the opening 93 in the top of shell or casing 91 is shown surrounded with a 105 suitable shield 95, see Figs. 8, 9 and 14.
- 110 Rotatably mounted on the under side of the top of shell or casing 91 is a disk 96; see Fig. 14, pivotally mounted at the point 97. This disk 96 is provided with a number of slots 98 adapted to be brought into register 115 with the enlarged slot or opening 93 in the outer casing 91 and the comparatively large slot or opening 94 in the top of the inner shell or casing 51. The openings or slots 93 and 94 are located immediately above the slotted heads 77 and 78 of the levers 73 and 74, shown in Fig. 12. The slots 98 in the disk 96 are of different sizes and also located at different distances from the center of the disk, so that one of the slots 98 may be 120 brought beneath the large slot or opening in the outer casing and in alignment with the selected slot in the heads 77 and 78 of the levers 73 and 74. For example, the slot 98, shown in Fig. 14, beneath slot 93 of the 125 130

outer shell or casing, is adapted to align with the slots 79 adjacent the sides of heads 77 and 78; so that the device, as just described, will merely permit the insertion of 5 a coin of given dimensions, as, for example, a cent; while the other slot 98 in disk 96, when brought beneath the opening 93 of the outer shell or casing, is adapted to register with an intermediate slot 79 in heads 77 and 10 78, thereby setting the device to receive a coin of different dimensions as, for example, a five cent piece. The disk 96 may be provided with additional slots at a proper distance from the center commensurate with 15 the width of heads 77 and 78, adapted to register with different sized slots in the heads 77 and 78, so that the device will be adapted to receive a third or additional number of 20 coins of different dimensions and denominations.

The periphery of disk 96 is shown provided with a number of indentations 99, which enable the disk 96 to be locked against rotation under normal conditions by the lock 25 92, as disclosed in Fig. 14; so that after the machine has been "set," it will be impossible for disk 96 to be accidentally or otherwise rotated, except through the operation of lock 92 into unlocking position by the use 30 of a proper key. Lock 92 therefore not only unlocks casing 91 from casing 51, but, by its operation, is also put into a position which will permit rotation of disk 96; access to the disk 96 only being had from the under 35 side of shell or casing 91.

In order to direct the inserted coin into the coin-receptacle 87, after the coin has passed through the composite slot of the heads 77 and 78, the side wall of the inner 40 shell or casing 51 is shown provided with a suitable guide 100, see Figs. 8 and 9, the lower end whereof is curved slightly away from the side wall or shell 51, thereby directing the coins to the side of the levers. 45

The outer shell or casing 91 may also be used as a means for holding suitable advertisements or other inscription. We have shown the top of shell or casing 91 provided with the upwardly presented frame portion 50 101, formed so as to permit the insertion of a card, as at B, provided with the desired advertisement or inscription. The card B is preferably inserted within the frame 101 from the bottom so as to prevent the improper removal thereof. In order to permit 55 access to frame 101, for the purpose of inserting or withdrawing the card B, we have shown the frame 101 removably secured to the top wall of shell or casing 91 by means of the butterfly nuts 102, see Fig. 10, which screw on the depending screw-rods 103 secured to the frame-member 101 and extending through suitable openings in the top wall of outer shell or casing 91.

60 In Fig. 4, we show a modified form of our

invention, in so far as the cooling chamber is concerned, as well as a different method of mounting the cup or dip-member. Instead of providing the upper portion of the body or tank 20 with an insulated wall like that 70 shown in Fig. 1, the upper portion is adapted to receive a suitable receptacle or ice-holding vessel 104, composed of suitable material such as fiber and the like, arranged not to interfere with the insulation-holding 75 portion 34 of the cover 34.

The receptacle or vessel 104 is provided with a liquid-holding vessel 30^a, preferably of vitreous ware, so made as to permit sufficient space for the insertion of ice within 30 the vessel 104 about the water-receiving vessel 30^a.

The water-receiving vessel 30^a is provided with an intermediate wall or partition 105 which, with the rear wall of vessel 30^a, is 85 adapted to constitute the bottle or container-receiving portion; the upper ends of the intermediate wall 105 and the rear wall being extended through an opening in the top 34 of the tank and suitably flared to receive the 90 inverted container or bottle 24. The front wall of the vessel 30^a, like the vessel shown in Fig. 2, is provided with a suitable extension 36^a to receive the liquid discharge from the cup or dipper-member 106; the extension 95 36^a being provided with an outlet to which is connected the discharge spout 37, as in the previously described construction.

The front wall of the vessel 30^a, at a point 100 within the extension 36^a, is provided with an opening or slot for the passage of the spout-portion 107 of cup or dipper-member 106. In this construction, the spout 107 is so formed or bent that the cup or dipper-member 106 may be suspended from the front 105 wall of receptacle 30^a and therefore oscillate on the front wall of the receptacle 30^a, as shown in Fig. 4. The spout-portion 107, is shown provided with the semi-circular groove 108, as more clearly shown in Fig. 6. 110

The spout 107, like spout 42, is also provided with an upwardly presented extension 44^a provided with the elongated slot 45^a adapted to receive pin 46 on the lower end of lever 47, which latter is operated through 115 the manipulation of slide or plunger 56.

The neck of the container or bottle 24 is shown provided with an extension 49, like in Fig. 1, in order to bring the outlet of the bottle or container into a horizontal plane 120 beneath that of the opening in the front wall of vessel 30^a through which spout 107 passes, so that the level of the liquid in vessel 30^a may act as an automatic seal for container or bottle 24 and prevent the flow 125 therefrom except in quantities commensurate with the amount that is being withdrawn from vessel 30^a, from time to time, through operation of cup or dipper-member 106.

65 The cup or dipper-member 106, shown in 120

Figs. 4, 6 and 7, differs from the cup or dipper-member 43, in that the outlet or spout 107 is extended down substantially to the bottom of the cup or dipper and has its side wall provided with an elongated slot 109, see Fig. 7, communicating with the interior of the cup or dipper. The discharge or spout 107 is preferably substantially circular in cross-section and provided with the encircling band or regulating member 110, made of less width than the length of slot 109 and adapted to be slid lengthwise of the discharge or spout-portion so as to control the point of outlet from the cup or dipper-member. The slot in the spout 107, preferably terminates a short distance from the lower end of the spout so as to leave the imperforate portion 107^a in the lower part of the dipper, as shown in Fig. 6. This permits the encircling band or regulating member 110 to be moved upward a considerable distance without uncovering the lower end of slot 109. Such movement will prevent the liquid in the lower part of the cup or dipper-member 106 draining or discharging therefrom. It is evident from this construction that the quantity of liquid to be dispensed with each operation of the device may be controlled by the positioning of encircling band or regulating member 110; for example, by moving the band or member 110 upward on the spout-portion 107, without uncovering the lower end of the slot 109, a small quantity of liquid will be obtained with each operation of the device. On the other hand, a greater quantity of liquid would be dispensed with each operation of the cup or dipper-member 106, when the member or band 110 is moved to its extreme upward position so as to uncover the lower part of slot 109, as this would allow the entire contents of cup or dipper-member 106 to be drained therefrom.

The apparatus, as disclosed in Figs. 1 and 4, is provided with the drip-receiving funnel 111, mounted in the same vertical plane as discharge-spout 37, so as to receive the drip therefrom and direct the waste water into the waste vessel 25 located in the lower compartment of the tank 20. The funnel 111, as well as the opening in the side wall of the tank 20, through which the lower end of the funnel passes, is made of a size sufficient to permit the passage of used or discarded cups, which will be directed into the drip and cup-receiving vessel 25.

In Fig. 5, we show a modification of our invention adapted for private use where the coin-controlled mechanism is not desired. The construction, so far as the cooler or fiber ice-holding receptacle and cup or dipper-member are concerned, is substantially identical with the similar elements used in the construction shown in Fig. 4, except that the water-receiving vessel 30^b is not provided

with the forwardly presented extension 36^a, and the forward wall of the vessel 30^b is adapted to be in close proximity with the wall of the outer or ice receptacle 104, so as to permit the discharge or spout 107^a of the cup or dipper-member 106^a to extend through a suitable opening in the wall of the outer vessel 104. The cup or dipper-member 106^a, like cup or dipper-member 106, has a portion extending through an opening in the front wall of water-receiving vessel 30^b and is oscillatingly mounted thereon. The opening in the vessel 104 is provided with a suitable shell 112, provided with a plunger 113, the lower end whereof rests on a suitable boss formed on the discharge member or spout 107^a. It is evident from this construction that depression of plunger 113 will cause the cup or dipper-member 106^a to be tilted upward out of the position shown in Fig. 5 and force the outlet end of spout 107^a into a lower horizontal plane than the bottom of the cup or dipper-member 106^a, thereby allowing the liquid to be drained therefrom. The opening in the front wall of the liquid-receiving vessel 30^b is in a horizontal plane above that of the mouth or orifice of the inverted bottle or container 24, so that the liquid in vessel 30^b will automatically seal the container 24 and prevent flow from container or bottle 24 except when sufficient liquid is taken from vessel 30^b through the operation of the cup or dipper-member 106^a, whereby the level of the liquid would drop below the orifice of the bottle 24. The liquid-receiving vessel 30^b, like the liquid-receiving vessels previously described, is provided with the upwardly presented receiving-portion 105, adapted to extend through a suitable opening in the cover 114 of the outer vessel 104.

We have shown and described several exemplifications of our invention, but it will be understood that the constructions illustrated may be altered in certain respects without, however, departing from the spirit of our invention, and we do not wish to be understood therefore as limiting ourselves to the exact constructions shown and described.

What we claim is:—

1. In an apparatus of the class described, coin-controlled locking means, comprising a pair of spring-controlled pivoted levers adapted to oscillate toward and from each other, said levers being provided with heads having correlated coin-receiving slots of varying dimensions so that insertion of a predetermined coin will cause the head-portions of said levers to oscillate away from each other, in combination with a reciprocating member with which one of said levers normally engages.

2. In an apparatus of the class described, coin-controlled locking means comprising a

pair of levers pivoted at points intermediate of their ends, the upper ends of said levers being provided with heads having correlated coin-receiving slots of varying dimensions 5 while the lower ends of said levers are in locking engagement with each other, both of said levers being spring-controlled so as to normally maintain them in locking relation, in combination with a reciprocating member provided with projections adapted 10 to be engaged by one of said levers when the latter are in normal position.

3. In an apparatus of the class described, a casing provided with a coin-receiving slot, 15 a pair of levers pivotally mounted in said casing at points intermediate of their ends so as to oscillate toward and from each other, means whereby the lower ends of said levers are maintained in locking relation 20 with each other, the upper ends of said levers being provided with heads having correlated coin-receiving slots of varying dimensions, means arranged intermediate of the coin-receiving slot of the casing and 25 said heads whereby the requisite coin to be inserted is determined, in combination with a reciprocating member with which one of said levers engages when the latter are in normal position and reciprocation of the 30 member prevented.

4. In an apparatus of the class described, a casing provided with a coin-receiving slot, a pair of levers pivotally mounted in the casing at points intermediate of their ends, the 35 upper ends of said levers being provided with heads arranged in juxtaposition with said coin-receiving slot and having correlated coin-receiving slots of varying dimensions, a multiple slotted member arranged 40 intermediate of the coin-slot in the casing and said heads whereby the requisite coin to be inserted is determined when the predetermined slot of said member is brought to register with the predetermined composite 45 slot of said heads, in combination with a reciprocating member adapted to be held against reciprocation when the levers are in normal position.

5. In an apparatus of the class described, 50 a shell or casing having a coin-receiving opening, a reciprocating member mounted therein, a pair of levers pivoted in the casing intermediate of said opening and said member, said levers being pivoted at points intermediate of their ends with the lower ends of 55 the levers in holding engagement with each other, while the upper ends are provided with heads having correlated slots of varying dimensions, rotative means disposed in 60 intermediate of the opening in the casing and the lever-heads and provided with a plurality of slots of different dimensions arranged at separated points whereby the predetermined composite slot of said heads is 65 brought to register with the opening of the

casing, and means intermediate of the levers and said reciprocating member whereby the latter is released when said levers are oscillated through the insertion of a preselected coin.

6. In an apparatus of the class described, a casing provided with a coin-receiving opening, a member reciprocatingly mounted in said casing, a pair of levers disposed intermediate of said member and said opening 70 and pivoted so as to oscillate toward and away from each other, one of said levers being normally arranged in locking engagement with said member, the upper ends of said levers being provided with heads having correlated coin-receiving slots adapted to register with the opening in said casing, and a coin-controlling member operatively connected with said reciprocating member so as to pass intermediate of the lever heads and the coin-opening of the casing.

7. In an apparatus of the class described, a shell or casing having a coin-receiving opening in the top thereof, a member reciprocatingly mounted in said casing, a pair of levers pivotally mounted intermediate of said member and the coin-receiving opening, said levers being pivoted at points intermediate of their ends, the upper ends of said levers being provided with heads having correlated slots of varying dimensions, a slotted member secured to said casing intermediate of the coin-opening and the heads of the levers, the slots of said member being arranged at different points and of varying dimensions whereby the selective composite slot of said levers is brought into register with the coin-opening of the casing, means operatively connected with said reciprocating member adapted to move across the heads of said levers when said reciprocating member is released and cause the inserted coin to be forced through the composite slot of said levers.

8. In an apparatus of the class described, a receptacle having a coin-receiving opening, a plunger slidably mounted in the receptacle pivotally mounted in the receptacle intermediate of the opening and said plunger, a pair of spring-controlled levers whereby the plunger is normally locked against outward movement, said levers being provided with series of correlated slots of different dimensions adapted to receive coins of varying dimensions whereby the levers are moved out of locking engagement with the plunger, and means whereby the composite slot of said levers to receive the coin is determined.

9. In an apparatus of the class described, a receptacle, a plunger slidably mounted in the receptacle, a pair of levers pivotally mounted in the receptacle whereby the plunger is normally locked against outward movement, said levers being adapted to be moved out of locking engagement with the

plunger through the insertion of a preselected coin, an outer casing for said receptacle provided with a coin-receiving slot, and a member movably mounted beneath the slot in said outer casing whereby the requisite coin for unlocking said levers is determined.

10. In an apparatus of the class described, a receptacle provided with a coin-receiving opening, a plunger reciprocatingly mounted in said receptacle, a lever pivotally mounted in the receptacle and normally locking said plunger against outward movement, said lever being adapted to be moved out of lock-

ing engagement with the plunger through the insertion of a predetermined coin, and a 15 multiple-slotted member rotatably mounted in the receptacle beneath the coin-receiving slot whereby the requisite coin for moving the lever out of locking engagement with the plunger is determined.
